SIGNALING SYSTEM

Frank R. Bridges, Needham, Mass., assignor to
 The Gamewell Company, Newton Upper Falls,
 Mass., a corporation of Massachusetts

Application December 24, 1935, Serial No. 56,044

7 Claims. (Cl. 177—378)

This invention relates to signaling systems and more particularly to fire alarm and similar systems, which, as is well known, require provisions for reliable operation even under extremely adverse conditions as, for example, broken, grounded, or short circuited lines. Such provisions include in most cases the use of an emergency conductor, which is under certain conditions supplied with current impulses derived from the source normally supplying the signaling circuit with current. The present invention also utilizes a separate conductor, usually the ground, for emergency signaling, but provides improvements which render the operation of signaling systems of this type especially secure and certain.

The principal object of my invention is to provide a comparatively simple, rugged and therefore reliable, durable and inexpensive signal transmitting station or alarm box which is nevertheless adapted to perform the functions of more complicated devices for signaling under abnormal conditions through an emergency conductor, especially in circuits according to my Patent No. 2,056,709 of October 6, 1936, although it is understood that the new apparatus will provide these beneficial and novel functions in other installations.

Other objects and aspects of my invention will be apparent from the following description, by way of example, of a specific embodiment of the invention. This description refers to drawings, in which:

Fig. 1 represents a connection diagram of a signaling circuit including a sender according to the present invention;

Fig. 2 a side elevation of the contact and non-interference magnet portion of an alarm box incorporating my invention;

Fig. 3 is a schematical side elevation of the contacts of Fig. 2, showing the contact side by side instead of behind each other;

Fig. 4 is a detail view of the contact control mechanism shown in Figs. 2 and 3;

Fig. 5 a schematical representation of the spatial contact arrangement according to Fig. 2; and

Fig. 6 a schematical representation of a modified contact control arrangement.

Referring to Fig. 1, L denotes a signal line or loop leading to station terminals 1 and 2 and containing a number of signal transmitters, herein referred to as alarm boxes R, R', R'' which normally keep the signal loop closed and their ground connections open. Busses DC supply direct current of suitable voltage derived from any

convenient source, and leads 3 and 4 of the direct current circuit D connect terminals 1 and 2 to these busses. Lead 3 contains an inductance 10 intermediate terminal 1 and its direct current bus, and a signal recorder X is inserted in lead 4 between terminal 2 and the other direct current bus. Although the signal recorders are herein indicated as being of the tape imprinting type, it is understood that any signal manifesting device may be used instead as, for example, acoustic means or relays controlling separate signal manifesting or repeater circuits. A battery B, in the nature of a so-called floating reserve power supply, may be connected across leads 3 and 4.

Busses AC supply alternating current, preferably from the public utility line, to the primary 11 of a transformer T. One terminal 14 of the transformer secondary 12 is grounded, whereas the other terminal 15 leads to conductor 7, which is part of an alternating current circuit A including lead 5 connected to terminal 1, a capacitance 21, an inductance 23, recorders Z and Y, an inductance 24, a capacitance 22 and lead 6 connecting to terminal 2. Inductances 23 and 24, in series with condensers 21 and 22, are provided for the purpose of compensating the phase displacing effect of the capacitances, in order to decrease as far as possible the impedance of the alternating current circuit.

The direct current derived from busses DC continuously supplies the signal loop L, so long as the latter is not interrupted by the code signal sending means of an alarm box, or by a break in the line. Condensers 21 and 23 prevent direct current from entering circuit A, whereas circuit D is protected from alternating current by choke coil 10 which is so dimensioned that its inductance presents an alternating current resistance of a magnitude excluding for practical purposes the alternating current of A. It will be obvious to any one skilled in the art, that inductance 10 passes substantially only direct current and that capacitances 21 and 22 pass substantially only alternating current, so that the loop L may carry superposed direct current and alternating current, whereas alternating current is excluded from circuit D and direct current from circuit A.

The signal transmitters R, R' and R'' according to my invention have a normally closed shunting switch 70 which opens when the box is pulled and remains open so long as the box movement is operative, namely, so long as the double code wheel 90 rotates. Arrangements of this type are well known in the art and for example shown at d⁴ of Fig. 1 of Patent No. 553,838 to F. W. Cole. 55

The double code wheel 90 comprises two identical toothed portions on a common shaft 190 and is adapted to actuate two sets of switch levers 96 and 97, 98 and 99, respectively. Switch springs 96 and 97, and 98 and 99, respectively, are mounted on blocks of insulating material which electrically separate the switch levers but permit their joint operation by the code wheel, which upon rotating lifts and drops levers 97 and 99. 5

In parallel with the shunting switch are spring contacts 96 and 97, connected to the signaling lines leading to terminals 1 and 2, respectively. Spring contacts 91 and 92 are connected to the terminals of a non-interference magnet 100, operating substantially only with direct current, and 10

Although this is not absolutely necessary, a switch with contacts 108, 109 may be provided between ground and conductor 95. This grounding switch is preferably operated together with the above described shunting switch 70, so that the alarm box is only grounded during operation

of the box. This grounding switch has principally the function of an auxiliary gap preventing break down for example in case of an accidental connection of the signaling circuit with a power line. 5

The above described arrangement with two code wheels on a common shaft, although capable of satisfactory operation, may under circumstances introduce the difficulty of necessitating exact alignment of the cams which, if not operating their respective switches with the proper time relation may cause unsatisfactory operation. Hence, an arrangement providing the same function, but having only one code wheel, is preferable for practical purposes. An arrangement of this 15 type is shown in Figs. 2, 3, 4, and 5.

As will be seen from Figs. 2 and 3, the arrangement of switches, magnet and line connections is exactly as in Fig. 1. Instead of having separate code wheels, contact groups 91, 92, 96, 97 and 93, 20 94, 98, 99 have separate followers 210 and 211, respectively, pivoted at 212 and moving the contact springs by means of insulator tips 215, 216. One of the followers, for example 210, is directly operated by a code wheel 290, as shown in Fig. 4. 25 From follower 210 extends a rod 69 across to follower 211 engaging it in a recess thereof, so that the two followers and the two contact groups necessarily move concomitantly. As above described with reference to Fig. 1, contacts 93, 98 30 and 94, 99 respectively close, and establish connection to ground shortly after contacts 91, 96 and 92, 97 respectively are opened. Pin 50 operates in this instance with follower 211 which is prevented from dropping if 50 is moved in front 35 of surface 251 of follower 211. Contacts 91, 96, 92, 97 are then prevented from opening, exactly as above explained with reference to Fig. 1, whereas the operation of contacts 93, 94, 98, 99 is not affected. It will now be evident without 40 further explanation, that this arrangement operates as described in connection with Fig. 1.

Under normal conditions of the signaling circuit the new system operates as follows: If the line is wholly normal and none of the boxes is 45 operated or "pulled", no alternating current flows in any part of the circuit since only one terminal of secondary 12 is connected thereto. Direct current flows in circuits D and L and is excluded from circuit A by condensers 21 and 22 as herein-before described. Recorder X is normally energized, whereas recorders Y and Z are deenergized and, upon operation of a box, signals are received at X, recorders Y and Z remaining inoperative. The non-interference arrangement of the box 55 operates exactly as in a non-grounded system. However, boxes of the type according to the present invention keep the signaling circuit closed, but establish ground, and signal over ground each time when the non-interference magnets are deenergized upon a box being pulled, so that the signals of two simultaneously sending boxes are received correctly. For example, if box R'' is pulled first and box R somewhat later, the direct current signals of R'' are received at X, whereas 60 two alternating current circuits are established by box R through ground and two branches of the signal loop, and corresponding signals are received at Y and Z. Box R signals over Y and Z while box R'' operates, whereas upon R'' stopping 65 and releasing the direct current circuit, box R assumes control of the direct current circuit and its remaining signal impulses are also received at X.

In the case of a broken circuit, as indicated at c 75

of Fig. 1, the direct current is interrupted, recorder X drops its armature and becomes incapacitated, and substantially no current flows in the system.

5 Assuming now an accidentally grounded signal loop as indicated at g in Fig. 1, the direct current recorder or relay X remains energized, since the direct current circuit is not interrupted, but alternating current circuits including ground g and the 10 respective adjacent branches of the signal loop are now established in addition, so that recorders Y and Z are also energized and their armatures attracted, indicating the faulty condition of the circuit. Since the direct current circuit is 15 normal, correct signals are received at X from all boxes just as if ground g were not present.

If a short circuit exists across a signal box, for example, around box R'' as indicated at m in Fig. 1, this box is not able to signal over the direct 20 current circuit since it is by-passed with respect thereto, but its signals are correctly received at recorders Y and Z , since upon becoming deenergized, the boxes drop the armatures of their direct current responsive non-interference magnets and signal through ground as above described.

If both boxes R and R'' , for example, are simultaneously pulled, both transmit understandable signals, box R over recorder X and box R'' 30 over the alternating current recorders.

A short circuit across the entire signaling loop, as indicated at n of Fig. 1, influences the circuit as follows: Any one of the short circuited boxes is able to send signals over ground, which 35 signals are received at X and/or Y . However, under this condition, two or more simultaneously pulled boxes produce mixed signals since the non-interference mechanisms of all short circuited boxes are incapacitated upon being deprived of 40 their energizing direct current.

In circuits utilizing a transformer secondary 42 in series with the signaling loop, and having a grounded intermediate terminal (as shown in Fig. 2 of application Serial No. 620,683), my new 45 alarm box functions in similar manner.

Instead of mechanically locking (as with stop 50) the normal signaling contacts 91 , 92 , 96 , 97 in closed position upon deenergization of the non-interference magnet, a similar effect can be obtained 55 electrically in a manner now to be described by way of example with reference to Fig. 6. In this figure, there are again four contact pairs $91-96$, $92-97$, $93-98$ and $94-99$. However, contact pairs 91 , 92 and 93 , 94 , which are in 60 different switch units in Figs. 1 to 5, are now electrically connected and mounted on contact springs 224 and 213 , respectively. A single code wheel 390 with follower 310 operates both contact units by means of insulating actuator 315 and likewise insulating connector 316 . It will be noted 65 that contacts $94-99$ and $93-98$ are normally open and contacts $92-97$ and $91-96$ normally closed, establishing exactly the same circuit connections as the embodiments shown in Figs. 1 to 5. In addition, two shunting switches 301 and 302 are provided, having contacts 324 , 397 , 313 and 396 connected to contacts 224 , 97 , 213 and 96 , respectively. Contact pairs $324-397$ and $313-396$ are normally retained open by means of 70 pin 350 which is actuated by the non-interference magnet 100 . The actuating mechanism of pin 350 may correspond exactly to that of pin 50 of Figs. 1 to 5 and is therefore not again shown in Fig. 6. If the armature is attracted as shown in Fig. 2, pin 350 is in the position shown in full

lines in Fig. 5, and keeps switches 301 and 302 open. If the magnet 100 becomes deenergized and its armature drops, pin 350 moves to the position shown in dotted lines in Fig. 6, and spring contacts $324-397$ and $313-396$ close.

It will now be evident that this arrangement functions like the one previously described. Namely, during normal operation, contact pairs $93-98$ and $94-99$ close, and contact pairs $92-97$ and $91-96$ open every time when follower 310 drops into an interdental space of code wheel 390 . If, however, the dropping armature of the non-interference magnet has retracted pin 350 from contacts 396 and 397 , switches 301 and 302 close, shunting contacts $91-97$ and $94-96$, respectively, thereby preventing the opening of the normal signaling circuit at these points. Otherwise the function of this embodiment of my invention is exactly as described with reference to Figs. 1 to 5.

It should be understood that the present disclosure is for the purpose of illustration only and that this invention includes all modifications and equivalents which fall within the scope of the appended claims.

I claim:

1. A signal transmitter comprising two terminals, an auxiliary signaling connection, normally closed and normally open switching means connected in succession intermediate said auxiliary connection and each terminal respectively, signal initiating means for rhythmically opening and closing said first switching means and closing and opening respectively said second switching means, said second switching means being closed subsequently to the opening of said first switching means and opened prior to the closing of said first switching means, switch control means, and means responsive to the amount of current flowing therethrough for actuating said control means, said actuating means being connected to said terminals in series with said normally closed switching means, and said control means maintaining said normally closed switching means in effectively closed position so long as the current in said actuating means remains within a predetermined range.

2. A signal transmitter comprising two terminals, an auxiliary signaling connection, normally closed and normally open switching means connected in succession intermediate said connection and each terminal respectively, signal initiating means for rhythmically opening and closing said first switching means and in the same rhythm closing and opening respectively said second switching means, said second switching means being closed subsequently to the opening of said first switching means and opened prior to the closing of said first switching means, switch control means, and means responsive to the amount of current flowing therethrough for actuating said control means, said actuating means being connected to said terminals in series with said normally closed switching means, and said control means maintaining said normally closed switching means in effectively closed position so long as the current flow in said actuating means is substantially zero.

3. A signal transmitter comprising two terminals, an auxiliary signaling connection, normally closed and normally open switching means, conductors for connecting a normally closed and a normally open switching means in series intermediate said connection and each terminal respectively, signal initiating means for rhythmically opening and closing said first switching

- means and in the same rhythm closing and opening said second switching means, a non-interference magnet connected across the conductors intermediate the first and second switching means associated with each terminal respectively, and means controlled by said magnet and upon deenergization of the magnet retaining said first switching means in closed position during operation of said second switching means.
4. A signal transmitter comprising two terminals, an auxiliary signaling connection, normally closed switching means and non-interference means in series across said terminals, a normally open switching means between said normally closed switching means and said connection, and signal initiating means for rhythmically opening and closing said first switching means and in the same rhythm closing and opening said second switching means, said non-interference means retaining said normally closed switching means in closed position when deenergized.
5. A signal transmitter comprising two terminals, an auxiliary signaling connection, normally closed and normally open switching means connected in succession intermediate said connection and each terminal respectively, signal initiating means for rhythmically opening and closing said first switching means and in the same rhythm closing and opening respectively said second switching means, said second switching means being closed subsequently to the opening of said first switching means and opened prior to the closing of said first switching means, normally open shunting contacts in parallel with said first switching means, current responsive actuating means connected between said terminals in series with said normally closed switching means and means controlled by said actuating means for closing said shunting contacts as long as the current in said actuating means remains within a predetermined range.
6. A signal transmitter comprising two terminals, an auxiliary signaling connection, normally closed switching means and normally energized non-interference means connected in series across said terminals, a normally open switching means between a point of said series connection and said auxiliary connection, signal initiating means, actuating means intermediate said initiating means and said normally closed switching means for rhythmically opening and closing said normally closed switching means in response to said signal initiating means, a second actuating means intermediate said first actuating means and said normally open switching means for closing and opening said second switching means in the same rhythm, said non-interference means when deenergized arresting said second actuating means for retaining said normally closed switching means in closed position.
7. A signal transmitter comprising two terminals, an auxiliary signaling connection, normally closed switching means having contacts connected between said terminals, normally open switching means connected between said auxiliary connection and said terminals, signal initiating means for rhythmically opening and closing said first switching means and closing and opening respectively said second switching means, said second switching means being closed subsequently to the opening of said first switching means, and opened prior to the closing of said first switching means, means for controlling the effectiveness of said first switching means, and means responsive to the amount of current flowing therethrough for actuating said control means and connected to said terminals in series with said normally closed switching means, said control means maintaining a current path across said contacts so long as the current in said actuating means remains within a predetermined range.

FRANK R. BRIDGES.
